UNITED STATES PATENT OFFICE.

WILLIAM KAYLOR, OF MUSKOGEE, OKLAHOMA.

RAILWAY-RAIL AND JOINT.

1,001,201.

Specification of Letters Patent. Patented Aug. 22, 1911.

Application filed April 21, 1911. Serial No. 622,457.

To all whom it may concern:

Be it known that I, WILLIAM KAYLOR, a citizen of the United States, residing at Muskogee, in the county of Muskogee and State of Oklahoma, have invented certain new and useful Improvements in Railway-Rails and Joints; and I do declare the following to be a full, clear, and exact description of the invention, such as will enable others skilled in the art to which it appertains to make and use the same.

This invention relates to railway rails and joints, and more especially to those wherein the ends of the rails interlock; and the object of the same is to produce a rail joint wherein the rail ends are connected both by their interlocking and by means of a plate or chair, without the necessity for any bolts. This object is accomplished by the construction hereinafter more fully described and claimed, and as shown in the drawings wherein—

Figure 1 is a side elevation of the two ends of meeting rails which are connected by this improved joint and spiked to two adjacent ties. Fig. 2 is a plan view of the same. Fig. 3 is a central longitudinal sectional view of the same. Fig. 4 is a vertical cross sectional view taken on the line 4—4 of Fig. 3. Fig. 5 is a detail perspective view of the chair or plate. Figs. 6 and 7 are similar views of the key-end and the slot-end of two adjacent rails.

In the drawings the letters A and B designate two rails whereof the former is the key-end and the latter the slot-end of the rails themselves, and the letter C designates the plate or chair upon which these meeting ends rest when in place over the ties T. The latter may be of wood of any preferred construction forming no part of the present invention. The chair may be and by preference is made of about three-eighths sheet metal rolled into shape as described, although it could be cast or wrought. It comprises a base plate 1 which may have notches 2 in its edges disposed as shown or elsewhere and obviously for the passage of spikes; and through the base are formed holes 3 for the passage of other spikes, these holes being disposed at certain points as will be described below. Throughout most of the length of this base and forming a part thereof are upright flanges 4 rising therefrom and constituting a substantially U-shaped member or clamp whose sides converge slightly toward each other and are

provided along their upper edges with in-turned lips 5 for a purpose to appear.

Each rail throughout most of its length 60 comprises the usual tread, web, and base which need no further description; and near each end of the rail of either construction the web is thickened as at 10 and the base is widened as at 11 so as to produce a 65 shoulder 12 on either side, these enlarged portions extending from the shoulder completely to the end of the rail if it be the slot end as shown in Fig. 7 or about half way to the end of the rail if it be the key end 70 as shown in Fig. 6. Longitudinal grooves 13 in the outer faces of the thickened portions 10 at both sides thereof, are also common to both kinds of rail-ends, these grooves being for the close reception of the lips 5 75 of the flanges 4. The shoulders 12 at the inner ends of the widened portions 11 are so disposed that when spikes are driven through the holes 3 into the ties T, said spikes will rest against the shoulders and 80 the inner ends of the wider portions of the faces and hold the rail-ends together while also holding all parts down upon the ties, although the spikes within the notches 2 serve the latter purpose in addition if they 85 are used.

The key-end of the rail has its tread extended as at 20 beyond the point 21 where its base ends, and beneath and formed integral with said extended tread 20 is a 90 tongue 22 having a beveled extremity 23 for a purpose which will appear. Also there is formed integral with the end 21 of the base a lip 24 whose extremity is beveled as at 25. Finally, there are formed along 95 both sides of the tread 20 where it is extended beyond the ordinary tread of the rail, two flanges 26 which reach throughout its length.

The slot-end of the rail is cut off as at 30 100 short of the end 31 of its base and the same distance therefrom as the tread of the other rail is extended at 20 beyond the end 21 of its base, said cut-off portion 30 being undercut as at 33 to receive the beveled extremity 23 105 of the tongue 22. The thickened sides 10 of this rail-end are formed with a groove 32 between them for the reception of the tongue 22, and the end 31 is undercut as at 35 for the reception of the beveled extremity 25 of 110 the lip 24. Finally, the rail-tread is provided on its two opposite sides with flanges 36 which terminate on a line flush with the cut-off portion 30 as seen in Fig. 7. All

parts of both rail-ends are formed integral in the act of making the rail, and it is my intention that one end of each rail shall be the key-end and the other the slot-end so that a 5 rail may be turned end for end at the time that two rails are to be connected with each other.

In assembling the parts of this rail joint, assuming that one rail has already been laid 10 and spiked except at the extremity which we are now to consider, first the plate or chair shown in Fig. 5 is slipped partway onto the rail which is partly spiked, the lips 5 of its flanges closely engaging the grooves 15 13 in a manner which will be clear and the disposition of the rail joint being such that the chair when in place will come above two of the ties. Next the complementary end 20 of the next rail to be applied is brought into position and its grooves 13 engaged with the projecting ends of the lips 5 and slipped into the clamp 4 until the end of its extended tread 20 comes against the cut-off tread portion 30 of the other rail, at which time the 25 ends 21 and 31 of the two bases will come together. As the rail-ends interlock the beveled extremities 23 and 25 engage the undercut portions 33 and 35 and the ends of the flanges 26 come against the ends of the 30 flanges 36. Thus the tongue 22 is caused to lie within the groove 32 and the two rail-ends are interlocked in a most thorough manner and over a considerable distance. By preference the proportion of parts is 35 such that the clamp 4 is just about as long as the thickened portions of the two rail-ends, while the base plate 1 is a little longer, and the holes 3 in the latter are so disposed that when the spikes are driven through them 40 into the ties their heads will stand behind the shoulders 12 of the webs and across the inner ends of the widened portions 11 of the treads of the two rail-ends so that the latter are absolutely prevented from moving apart 45 although permitted to have a slight expansion and contraction due to changing temperatures.

Thus it will be seen that I have produced an improved rail joint wherein no bolts are 50 employed and there are no nuts to come loose, wherein the rail-ends are always in alinement both vertically and transversely, and wherein such alinement in both directions is assisted by the chair and its clamp; 55 and especial attention is directed to the fact that the insertion of the spikes which are necessary to hold the chair to the ties is all that is required to hold the rail-ends from separation from each other. I have not 60 given the dimension of parts because that is not important to this invention. It will be observed that the flanges 26 upon the key-

end overlie the upper edges of the sides 10 of the slot-end so that no water or snow will get into said slots and cause the rail ends to 65 rust together, and so that dust and dirt are effectively excluded.

What is claimed as new is:

1. In a rail joint, the combination with two rails whose ends are thickened and 70 formed so as to interlock when they meet and having registering longitudinal grooves along the opposite sides of their thickened portions; of a chair comprising a base plate, upright flanges rising therefrom alongside said thickened portions, and inturned lips along their upper edges closely engaging said grooves.

2. In a rail joint, the combination with two rail-ends which are widened toward 80 their extremities so as to produce shoulders and are adapted to interlock; of a chair comprising a base plate having spike-holes through it at points adapted to stand behind said shoulders whereby the spike heads will 85 engage the latter, and a clamp on said plate engaging the sides of the widened portions.

3. The herein described rail joint comprising a key member and a slot member, the key member having its tread portion extended beyond its base portion, a lip on the latter having a beveled extremity, and a tongue extending along the lower side of the extended tread and having a beveled extremity; and the slot member having its 90 base portion extended beyond its tread portion a corresponding distance and the extended portion of the base being provided with a groove for the reception of said tongue, the cut-off portion of the tread and 100 the end of the base being undercut for the reception of said beveled extremities.

4. In a rail joint, the combination with a chair having a clamp; of the rail-ends whereof one has its tread portion extended 105 beyond its base portion and provided with a depending tongue, and the other has its base portion extended beyond its tread portion and provided with a groove for the reception of said tongue, and laterally projecting 110 flanges along both sides of each tread portion terminating flush with the end thereof so that the extremities of the flanges abut against each other when the rail-ends are assembled upon said chair and the top of said 115 groove is protected.

In testimony whereof I have hereunto set my hand in presence of two subscribing witnesses.

WILLIAM KAYLOR.
